UNITED STATES PATENT OFFICE.

ARTHUR E. HANSEN, OF SEATTLE, WASHINGTON, ASSIGNOR TO YOUNG IRON WORKS,
OF SEATTLE, WASHINGTON, A CORPORATION OF WASHINGTON.

CABLEWAY AND CARRIAGE.

Application filed March 20, 1924. Serial No. 700,624.

My invention relates to an improvement in cableways such as are employed in sky-line logging, for example, and to the carriages which are employed in connection therewith.

It is an object of my invention to provide a cableway and carriage by means of which the carriage may be stopped and held at both ends of its run along a trackway cable, and locked in this position until it is desired to release the carriage.

It is my object, also, in connection with such a cableway system and carriage, to provide means whereby the carriage will only be unlocked and released for further movement along the trackway cable by raising the fall block into engagement with and locking the same to the carriage.

It is a further object to provide means in a cableway and carriage whereby the fall block, which must be lowered from the carriage, shall be locked thereto while the carriage is between the ends of its run, and in which the fall block may not accidentally be lowered intermediate the ends of its run, but in which at the ends of the run the fall block is automatically released for lowering.

A further object is the provision of means in connection with such a cableway system and locking fall block, and one which is particularly intended for down-hill logging, whereby in the event the carriage gets out of control, the fall block may be dropped semi-automatically, thus dragging the fall block and its load along the ground and in this manner serving to check the carriage.

Still another object is the provision of a carriage carrying locking dogs at opposite ends for engagement with fixed stops at the end of the carriage's run, these dogs normally tending to lie in released position, and also a latch member operatively connected to these dogs and normally tending to lie in position to maintain the dogs in locking position, this latch being operable by the raising and lowering of the fall block.

My invention comprises the improved cableway system, together with the novel arrangement and combination of parts therein, and the novel carriage for use in such cableways, all as shown in the accompanying drawings, described in the specification and particularly defined by the claims terminating the same.

In the accompanying drawings I have shown my cableway arranged in a manner now preferred by me, and have shown my carriage in a form which is now preferred.

Figure 1 is a diagrammatic view of my cableway system illustrating the device arranged for logging down hill.

Figure 2 is a longitudinal central section through my carriage and associated parts.

Referring to Figure 1, which shows the entire cableway system, the head mast 9 and the tail mast 90 support between them a trackway cable 8. This would generally be a fixed sky-line, but might, if desired, be a sky-line of the slack type, as is common in the art. Along the trackway cable 8 a carriage, generally designated by the numeral 1, is movable. The movement of the carriage is suitably controlled, as, for example, by a hauling line 80 and a back-haul line 81. The hauling line may be so rigged through the carriage 1 that it supports also a fall block 2, and thus its end forms a hoist line 82. The back-haul line may be connected to the carriage 1 through a connection to the fall block 2, and thus the back-haul line serves the dual purpose of returning the carriage 1 toward the tail mast 90, and of hauling down the fall block 2 against the weight of the hauling line 80. These various lines are suitably guided and are controlled from a central point, as, for example, by the drums 83 and 84 forming part of a donkey engine.

The carriage 1 is supported from the trackway cable 8 upon suitable sheaves 10. As it is free to run on these sheaves, and as both ends of the cable 8 will sag towards the center, notwithstanding that one end may be lower than the other, it is necessary, in order to release and drop the fall block, that the carriage be otherwise held than by the lines 80 and 81, and so held at both ends of its run. Means are provided, therefore, at each end of the run of the carriage, and independent of the traversing cables, whereby it may be held in position and prevented from further movement along the cable until it is desired again to move the carriage.

Such means may comprise a pair of fixed stops 3, secured upon the trackway cable 8 or elsewhere at opposite ends of the run of the carriage, these stops being suitably engaged by the shoulders of a dog 4. Two such dogs are employed, these being pivoted

between their ends at 41, at opposite ends of the carriage and projecting therefrom to engage each its respective stop 3. The dogs 4 are weighted so that they normally lie in a released position, but are so positioned that as the carriage reaches one of the stops 3, the shoulder 42 of the dog at this end will strike the stop 3 to raise its weighted end, whereupon the stop is engaged and held between the shoulder 42 and the normally slightly lower shoulder 43 of the dog. Means are provided for locking the dogs thereupon in this position, and in consequence the carriage is held in this position by the engagement of this dog with its stop 3 and cannot be moved until the dog is released. Preferably both dogs are connected to operate simultaneously, and thus connected form a carriage-positioning assembly, all parts of which are directly connected. Connection of the dogs may be secured by means of a link 44, pivoted at 45 below the pivot 41 of one dog and at 46 above the pivot of the other dog. Movement of the weighted end of one dog upward moves the other dog upward also, as has been indicated by dotted lines in Figure 2.

For retaining the dogs in upraised or locked position, I provide a latch 5, which is pivoted at 51 in the carriage, 1. Associated with this latch 5 is a weighted arm 52, this as shown forming a part of the latch. A cam surface 53 on the latch 5 will engage an end of a bolt or locking bar 54, which is connected at 55 to one of the dogs 4, to maintain this bolt 54 projecting in a position corresponding to locking position of the dogs, so long as the weighted arm 52 is in its lowered position, as shown by dotted lines in Figure 2. However, a recess or shoulder 56 interrupts the cam surface 53 and is registrable with the end of the bolt 54 when the weighted arm 52 is upraised, and when in registry therewith permits reciprocation of the bolt 54 to permit the dogs 4 to drop of their own weight into released position. The shoulder 56 is thereupon engaged by the bolt 54 to retain the weighted arm 52 in upraised position until it is desired to release it.

I have shown the hauling line 80 as guided over a sheave 11, thence through a sheave 21 secured in the fall block 2 and thence extending to a pin 12 in the carriage, to which its end is secured, though the precise arrangement is largely immaterial. The portion between the sheave 11 and the pin 12 forms the hoist line 82. Between the sheave 11 and the pin 12, and immediately above the normal path of the fall block 2, the lower edge of the carriage is notched as indicated at 13, and a pin 23, projecting upwardly from the fall block 2, enters this notch 13 as the fall block is lifted. It is guided by the converging sides of the notch 13 into engage-

ment with the weighted arm 52 when the latter is down, the pivot 51 being to one side of the notch 13, and by its upward movement raises the arm 52. The latch 5 may be formed with a hook 57 which, as the latch 70 and its arm 52 are swung upward, engages beneath the pin 23 of the fall block.

Such action starts when the fall block is lowered, when one of the dogs 4 is engaged with its stop 3, and when the weighted arm 75 52 is in the position shown in dotted lines in Figure 2, that is, when the bolt 54 holds the dogs locked by reason of its engagement with the cam surface 52. As the pin 23 engages the arm 52 and raises it, movement of the latch 5 moves its cam surface over the end of the bolt 54 until at the time the pin 23 is supportingly engaged by the hook 57, the end of the bolt 54 drops engagement with the shoulder 56 under the 80 weight of the dogs 4 and associated mechanism as the dogs are released. At the time, however, engagement of the bolt with the shoulder 56 prevents a reverse movement of the latch 5 and maintains the hook 57 in 90 position to support the fall block 2.

The carriage is then in condition to be moved along the trackway cable 8, the fall block being locked thereto. It is then traversed by means either of the hauling line 95 80 or the haul-back line 81, and during movement along the sky-line 8 there is no way in which the bolt 54 may accidentally be retracted. However, upon reaching the opposite end of its run the dog 4 at this 100 end of the carriage, by engagement with its stop 3, is raised, the dog at the opposite end being likewise raised, and the bolt 54 is retracted. This withdraws the locking means for the fall block and permits the 105 weighted arm 52 to drop. The fall block 2 is thereupon placed in position to be lowered, and its lowering is controlled through the line 80.

In long spans, and especially when 110 going down hill, even though the span be a short one, there is a tendency for the carriage to run away down hill. If the span is substantially level the carriage will tend to run toward the center. If the span is 115 on a steep incline, the tendency is, of course, to run to the bottom of the incline. Such carriages, weighing hundreds of pounds unloaded, are tremendously destructive and highly dangerous if once out of control. In 120 order, therefore, to check the carriage if possible, and to stop it once it has gotten away from control, I have provided the safety means which I will now describe.

It is evident that so long as the bolt 54 125 is not retracted from engagement with the recess 56, the fall block cannot be dropped, but that if the bolt is retracted the fall block is free to drop. I therefore provide a downward extension 47 upon one of the 130

dogs 4 and a pivot trip lever 6 in the carriage in position to engage the extension 47. The trip lever 6 may be held in position so that it does not press upon the extension 47 normally, by some such means as the spring 61 and rod 62. An arm 63, also secured to move with the trip lever 6, has connected to it a safety line 60 which extends back to a drum 64 on the donkey engine.

10 Ordinarily the safety line 60 has no strain placed upon it, and consequently there is no pull upon the arm 63 except that due to the weight of the line 60. However, if it should be desired in an emergency to release the fall block 2, this may be done by checking the paying out of line from the drum 64, by some means common in the art, as by applying a brake to the drum 64. The result of this is to pull on the arm 20 63 and the trip lever 6, in opposition to the spring 61, whereupon the extension 47 is thrown to the right, as seen in Figure 2, and the bolt 54 is retracted. The latch 5 immediately swings over to position to release 25 the fall block 2, and if there is no tension on the line 80 the fall block immediately drops to the ground with its load, and acts as an effective drag to check and stop the runaway movement of the carriage 1.

30 What we claim as our invention is:

1. In a cableway carriage, a pair of angularly disposed locking dogs each pivoted at its angle and positioned at opposite ends of the carriage, one arm of each projecting laterally beyond the carriage and weighted to tend to remain in lowered, released position, the other arm extending downwardly, a third arm on one of said dogs extending upwardly from its pivot, a rod directly connecting said upwardly extending arm with the downwardly extending arm of the opposite dog, a bolt movable in the carriage and connected for movement to one of said dogs, a latch and hook member pivoted in the carriage and engageable by said bolt, said latch and hook member being weighted to retain said dogs in up-raised locked position when the hook is in load-releasing position, and movable to swing the hook into load-sustaining position and to release the dogs for movement by gravity into released position.

2. In a cableway carriage, a pair of angularly disposed locking dogs each pivoted at its angle and positioned at opposite ends of the carriage, one arm of each projecting laterally beyond the carriage and weighted to tend to remain in lowered, released position, the other arm extending downwardly, a third arm on one of said dogs extending upwardly from its pivot, a rod directly connecting said upwardly extending arm with the downwardly extending arm of the opposite dog, a bolt movable in the carriage and connected directly to the lower end of

one of said dogs, a latch and hook member pivoted in the carriage and weighted to tend to position the hook in load-releasing position, said bolt engaging said latch member at such times to retain the dogs in up-raised locking position, said latch and hook member being swingable to bring the hook into load-sustaining position, the bolt at such times being engageable therewith to retain the hook in load-sustaining position, and being movable into such engagement by gravitational movement of the dogs into releasing position.

3. In a cableway carriage, a pair of angularly disposed locking dogs each pivoted at its angle and positioned at opposite ends of the carriage, one arm of each projecting laterally beyond the carriage and weighted to tend to remain in lowered, released position, the other arm extending downwardly, a third arm on one of said dogs extending upwardly from its pivot, a rod directly connecting said upwardly extending arm with the downwardly extending arm of the opposite dog, a bolt movable in the carriage and connected directly to the lower end of that dog having the upwardly extending arm, a latch and hook member pivoted in the carriage and weighted to tend to position the hook in load-releasing position, said bolt engaging said latch member at such times to retain the dogs in up-raised locking position, said latch and hook member being swingable to bring the hook into load-sustaining position, the bolt at such times being engageable therewith to retain the hook in load-sustaining position, and being movable into such engagement by gravitational movement of the dogs into releasing position.

4. In a cableway system, a trackway cable, a carriage movable therealong, a stop fixed at each end of the run of said carriage, a fall block hoisting means therefor, a pair of simultaneously operable locking dogs upon the carriage each engageable with its respective one of said fixed stops, and means operatively connected to said locking dogs for retaining them in locking position until said fall block has been raised to a predetermined position beneath the carriage, and for retaining said fall block in such raised position thereafter until one of said dogs is engaged with its fixed stop, a spring-held trip lever, a member in the locking system engageable thereby, when the trip lever is moved in opposition to said spring, to release said fall block, and a safety line operatively connected to said trip lever and extending to a distant point.

5. In a cableway carriage, a pair of angularly disposed locking dogs each pivoted at its angle and positioned at opposite ends of the carriage, one arm of each projecting laterally beyond the carriage and weighted to tend to remain in lowered, released position,

- the other arm extending downwardly, a third arm on one of said dogs extending upwardly from its pivot, a rod directly connecting said upwardly extending arm with 5 the downwardly extending arm of the opposite dog, a bolt movable in the carriage and connected for movement to one of said dogs, a latch and hook member pivoted in the carriage and engageable by said bolt, said latch and hook member being weighted to 10 retain said dogs in upraised locked position when the hook is in load-releasing position, and movable to swing the hook into load-sustaining position and to release the dogs 15 for movement by gravity into released position, a downward extension on one of said dogs, a trip lever yieldingly held in engagement with said extension, and means connecting said trip lever with a distant 20 point for actuating said dogs and the associated mechanism to effect release of the hook at will.
6. In a cableway carriage, a carriage positioning assembly comprising a pair of locking dogs at opposite ends of the carriage and 25 projecting therefrom, said dogs being pivoted and weighted to tend to remain in lowered, released position, and a rod directly connecting said dogs for simultaneous movement, a bolt movable in the carriage and directly connected to and movable with a member of said positioning assembly, a latch and hook member pivoted in the carriage and engageable by said bolt, said latch and hook member being weighted to retain said 30 dogs in upraised, locked position when the hook is in load-releasing position, and movable to swing the hook into load-sustaining position and to release the dogs for movement by gravity into released position. 35

Signed at Seattle, King County, Washington.
